UNITED STATES PATENT OFFICE.

GEORGE W. CLAPP, OF GREENSBORO, NORTH CAROLINA, ASSIGNOR OF TWO-THIRDS TO GURNEY G. CLAPP AND CARL J. CLAPP, OF GREENSBORO, NORTH CAROLINA.

IRONING-TABLE.

SPECIFICATION forming part of Letters Patent No. 732,394, dated June 30, 1903.

Application filed September 25, 1902. Serial No. 124,815. (No model.)

To all whom it may concern:

Be it known that I, GEORGE W. CLAPP, a citizen of the United States, residing at Greensboro, in the county of Guilford and State of North Carolina, have invented a new and useful Ironing-Table, of which the following is a specification.

This invention relates to improvements in ironing-tables, and has for its object the production of a simple and inexpensive foldable ironing board or table securely braced and supported and provided with automatically-operating supporting-props and a flat-iron heater in convenient position adjacent to the ironing-board; and the invention consists in certain novel features of construction, as hereinafter shown and described, and specified in the claims.

In the drawings illustrative of the invention, Figure 1 is a perspective view of the device extended as in use. Fig. 2 is a longitudinal sectional elevation of the device extended. Fig. 3 is a longitudinal sectional elevation of the device closed or folded for transportation or storage.

The improved device consists in a supporting-frame having foldable supporting-legs for maintaining it in an inclined position, with an ironing-board hinged to the frame at one end and adapted to be supported at its free end in operative position by a spring-controlled prop, the spring of which exerts its force to assist in elevating the ironing-board into operative position. This prop is limited in its outward movement and yieldable inwardly to permit skirts and similar garments to be readily placed on the board between it and the free end of the board. This board is also provided with an auxiliary spring-controlled support disposed adjacent to the hinged end of said board to firmly support the board, so that the free end thereof may be unobstructed for convenience in ironing skirts and such like garments.

The framework consists of spaced side members 10 11, connected at the ends by transverse plates 12 13, and one or more intermediate rounds or braces 14.

The framework may be of any length desired and of any suitable width, but will gen-

erally be of the usual dimensions of devices of this character.

Hinged to one end of the supporting-frame are leg members 15 16, connected by a transverse bar 17, the latter affording means for the engagement of the movable brace member 18, connected to the framework at 19, as shown. By this arrangement it will be readily understood the leg members may be supported in their outward position, and thus maintain the supporting-framework in its inclined operative position, as shown in Figs. 1 and 2. The ironing-board is represented at 20, hinged by one end at 21 to the framework, the hinging feature being preferably formed by a transverse round rotatively engaging the side pieces 10 11 and supporting the ironing-board, as shown. By this means the ironing-board may be folded down against the framework, as shown in Fig. 3, or elevated into operative position, as shown in Figs. 1 and 2.

The plate 13 will be provided with an aperture or other means for supporting a flat-iron heater of any approved form, and for the purpose of illustration a conventional flat-iron heater is illustrated at 22, supported upon the plate 13 detachably, so that the heater may be removed when the device is not in use. It will be noted that the heater is thus supported in position convenient to the ironing-board 8, 20, so that much valuable time will be saved in operating the device, as the flat-iron may be kept heated and in position convenient for the operator.

Transversely disposed between the lower ends of the side members 10 11 is a rotative bar 23, supporting-props 24 25, adapted when in their extended position to engage the lower surface of the ironing-board near its free end and thus maintain the board in operative position, the leg members 24 25 being thus foldable into position nearly parallel to the side members 10 11 when not in use. The bar 23 will be provided with a spring 26, disposed to exert its force to maintain the prop members normally in their elevated position and also to cause them to assist in elevating the ironing-board into operative position, as will be obvious. The bar 23 is provided with a projecting stud 27, adapted to engage a projection upon the 100

- plate 12 when the prop members are elevated, and thus limit the backward movement of the prop members. The stud 27 is also adapted to serve as a catch to yieldably engage a plate 5 28 upon the lower side of the ironing-board when the latter is depressed, as shown in Fig. 3, and thus yieldably lock the ironing-board in its folded position. The stud 27 will engage the plate 28 with sufficient force to prevent 10 its accidental displacement, but will be sufficiently resilient to yield to the pressure exerted in moving the ironing-board away from the framework when it is desired to use the device. This makes a very simple and complete means of connecting and supporting the ironing-board or locking it yieldably in its closed position.
- When it is desired to set up the device, the leg members 15 16 are extended and the brace 20 member 18 connected to the transverse bar 17. The ironing-board is then forcibly disconnected from the stud 27, which action will release the prop members 24 25, so that the spring 26 will exert its force to elevate the prop members, pressing them against the underside of the board and assisting in elevating it into its operative position, the prop members being prevented from moving too far backward by the stud 27 engaging the projection on the 25 plate 12, as above noted. The flat-iron heater 22 is then placed in position upon the plate 13. Transversely disposed across the framework and rotatively engaging the side members 10 11 is a bar 29, having standards 30 31 extending 30 therefrom and adapted when in their elevated position to engage the lower surface of the ironing-board 20 comparatively near its hinged end, as shown. The bar 29 is provided with a spring 32, adapted to exert its force to maintain the standards 30 31 in their upward or 35 extended position, so that when the ironing-board is elevated the standards 30 31 will automatically follow it in its upward movement and assist in elevating it and likewise support 40 the ironing-board. By this means the board will be firmly supported independently of the support afforded by the prop members 24 25, so that when skirts are to be ironed they may be passed over the free end of the ironing- 45 board and the prop members 24 25 depressed thereby and disconnected from engagement with the ironing-board without causing the

ironing-board to fall or be released, as it will be amply supported by the auxiliary supporting members 30 31. By this means it will be obvious skirts and similar garments may be placed upon the ironing-board in convenient position for ironing without detaching any parts except to turn the spring-controlled prop members 24 25 downward, as above 55 noted, and this will be done automatically by the friction of the garments therewith. This makes a very complete, simply-operated, and cheaply-constructed device, which may be readily and quickly extended into operative 60 position or folded together when not required or when it is to be transported.

The parts may be modified and changed in minor particulars without departing from the principle of the invention or sacrificing any 70 of its advantages.

Having thus described the invention, what is claimed is—

1. An ironing-table comprising a supporting-frame, legs hinged to said frame for supporting it in inclined position, an ironing-board hinged at one end to said frame, a spring-controlled prop hinged to said frame in position to support the free end of said board, said prop being yieldable inwardly 80 against the tension of its spring, and means for limiting the outward movement of said prop.

2. An ironing-table comprising a supporting-frame, legs hinged to said frame for supporting it in inclined position, an ironing-board hinged at one end to said frame, a spring-controlled prop hinged to said frame in position to support the free end of said board, said prop being yieldable inwardly, 85 means for limiting the outward movement of said prop, and an auxiliary spring-controlled board-support disposed adjacent to the hinged end of said board to firmly support it in operative position when the prop for the free end 90 is withdrawn.

In testimony that I claim the foregoing as my own I have hereto affixed my signature in the presence of two witnesses.

GEO. W. CLAPP.
